GOLF CLUB

Kay R. Williams, 1011 N. Holmes St.,
Indianapolis, Ind. 46222

Filed Mar. 14, 1969, Ser. No. 16,256

Term of patent 14 years

Int. Cl. D21—03

U.S. Cl. D34—5

FIG. 1 is a side elevation of the golf club embodying the present invention.

FIG. 2 is an enlarged top plan view of the head of the golf club of FIG. 1.

FIG. 3 is a rear elevation of the head illustrated in FIG. 2.

FIG. 4 is a side elevation of the head illustrated in FIGS. 2 and 3.

FIG. 5 is a front elevation of the head illustrated in FIGS. 2, 3 and 4.

FIG. 6 is a bottom plan view of the head illustrated in FIGS. 2, 3, 4 and 5.

The side opposite FIG. 4 is substantially the same as that shown.

I claim:

The ornamental design for a golf club, as shown and described.
